UNITED STATES PATENT OFFICE.

ANNA DEANE BAILEY, OF NEW YORK, N. Y., ASSIGNOR, BY DIRECT AND MESNE ASSIGNMENTS, TO G. H. MASTEN CO., INC., OF NEW YORK, N. Y., A CORPORATION OF NEW YORK.

LIFE-PRESERVER.

1,366,345.

Specification of Letters Patent. Patented Jan. 25, 1921.

Application filed June 1, 1918. Serial No. 237,793.

To all whom it may concern:

Be it known that I, ANNA DEANE BAILEY, a citizen of the United States, and a resident of the borough of Manhattan, city, county, and State of New York, have invented certain new and useful Improvements in Life-Preservers, of which the following is a specification.

The object of this invention is to provide a durable and inexpensive appliance which may be attached to the body very conveniently and quickly, and without confusion.

A further object of the invention is to provide simple and inexpensive means whereby the head and face of the wearer will be protected against undue buffeting by the waves.

In the drawings, Figure 1 is a plan view of the device extended; and

Fig. 2 is a side elevation of the device in position for use.

The front or chest member A of the appliance consists preferably of a series of vertical buoyant members 1, flexibly connected together at their vertical edges, and preferably consisting of a suitable fabric inclosing a block of cork or other buoyant material. The back member B is similarly constructed, the vertical buoyant members 2 being designated by 2. The front and back members are connected together by a flexible shoulder portion 3, said shoulder portion being a part of the fabric which incloses the buoyant elements of the front and back members. The shoulder portion 3 is provided with a large opening to permit the appliance to be passed downwardly over the head. The front and back members are also connected together by means of arm straps 4, said straps and the shoulder portions forming arm holes through which the arms are to be thrust when the appliance is passed downwardly over the head.

Secured to the shoulder portion of the appliance is a head-protecting float C, which consists of the front pillow 5, the rear pillow 6, said pillows being connected together by the comparatively thin shoulder-protecting pads or floats 7. The head-protecting float is formed with a large opening 8, which registers with the opening in the shoulder portion of the main body of the appliance, and the two parts of the appliance are connected together around the edges of the said head receiving opening. The head-protect-

ing float is provided with a draw-string or cord 9, which extends around the head-receiving opening, the two ends thereof being arranged at the front of the appliance, as shown clearly in Fig. 2. By means of 60 this draw-string the head-receiving opening may be contracted around the neck of the wearer to prevent the head dropping down through the opening, should the wearer become exhausted. By means of the draw- 65 string the front and back pillows will be drawn into proper position to support and protect the head, should the wearer become exhausted while in the water. The thinner shoulder portions of the head-protecting pad 70 will not obstruct the view of the wearer side- wise, so that a proper look-out for wreckage and boats may be had.

The back and front members of the appliance may be contracted to fit the body of the 75 wearer, and may be suitably secured in position by means of cords or tapes 10, secured to the back member and adapted to be passed through loops 11 on the front member or if desired, they may be passed entirely around 80 the body of the wearer and tied in front or at the back, as may be convenient.

In applying the device, it is only necessary to pass the head through the head-receiving opening and to thrust the arms 85 upwardly and outwardly between the arm straps and the shoulder portions of the main body of the appliance. The draw-string then may be pulled to contract the head-protecting float, and then the strings 10 may 90 be tied around the body part of the device. The proper method of applying the device to a wearer is obvious from a mere inspection of it, and this is a very essential feature in devices of this kind. 95

What I claim is:

1. A life preserver of the character described comprising body sustaining means, and head sustaining means connected to said body sustaining means and comprising front 100 and rear buoyant pillows spaced apart, connecting floats between said pillows and adapted to lie at opposite sides of the neck of the wearer, said connecting floats being compressible and extensible in a longitudinal direction whereby to admit of the front and rear pillows approaching each other or being moved farther apart, said front and rear pillows and said connecting floats having an opening therebetween to receive the 110

head of the wearer, and means associated with said head sustaining means for compressing the lateral floats and simultaneously drawing the pillows together about the head.

2. A life preserver of the character described comprising front and rear body sustaining members, a shoulder member connected between the upper ends of the first mentioned members and adapted to seat on the shoulders of the wearer, said shoulder member having an opening therein to receive the head of the wearer, a head sustaining member having an opening in registry with the opening in said shoulder member, said shoulder member and head sustaining member being secured together about said opening and being formed with a casing thereabout, a draw-string in said casing adapted to contract the opening about the neck of the wearer after the head has been inserted therethrough, lateral floats of compressible character on the head sustaining member at the sides of said opening for supporting and protecting the sides of the head, and front and rear pillows carried on the head sustaining member at the ends of said lateral floats and adapted to approach each other or to move apart accordingly as said draw-string is tightened or released.

3. A life preserver of the character described including front and rear body members, a shoulder member connected to the upper ends of said body members, straps also connected between the upper ends of

said body members in spaced relation to the shoulder member to provide the latter with armholes, a head sustaining member connected to said shoulder member and composed of front and rear pillows, narrow thin connecting floats arranged at the sides of the neck and being compressible, means to compress said side floats about the neck of the wearer, and means to secure the lower portion of the rear body member to the lower portion of the front body member.

4. A life preserver of the character described including a front body member composed of a plurality of sections flexibly connected together and including a horizontal series of strips of buoyant material, fabric coverings for said buoyant material forming flexible joints between adjacent strips, a rear body member formed of strips of buoyant material, with fabric flexibly connecting said strips together, a shoulder piece connected to the upper ends of said front and back members, a head sustaining member secured to said shoulder piece and composed of front and rear head supporting pillows and lateral floats of reduced thickness capable of being compressed, means for compressing said lateral floats about the neck of the wearer, and means for securing the lower portion of said back member to the lower portion of said front member and to clasp such members tightly against the trunk of the body.

In testimony whereof I hereunto affix my signature.

ANNA DEANE BAILEY.
